(57) **CLAIM**

The ornamental design for a foldable tent frame as shown and described.

DESCRIPTION

FIG. 1 is a front view of an embodiment of a foldable tent frame in a deployed position;

FIG. 2 is a rear view of the foldable tent frame depicted in FIG. 1.

FIG. 3 is a left view of the foldable tent frame depicted in FIG. 1.

FIG. 4 is a right view of the foldable tent frame depicted in FIG. 1.

FIG. 5 is a top view of the foldable tent frame depicted in FIG. 1.

FIG. 6 is a bottom view of the foldable tent frame depicted in FIG. 1.

FIG. 7 is a top-rear-right view of the foldable tent frame depicted in FIG. 1.

FIG. 8 is a bottom-rear-left view of the foldable tent frame depicted in FIG. 1.

FIG. 9 is a top-rear-right view of the foldable tent frame depicted in FIG. 1.

FIG. 10 is an enlarged view of a pivotal joint of the foldable tent frame depicted in FIG. 7.

FIG. 11 is an enlarged view of a pivotal support element of the foldable tent frame depicted in FIG. 7.

FIG. 12 is a view of a roof portion of the foldable tent frame depicted in FIG. 1, when the foldable tent frame is in a partially folded position.

FIG. 13 is an enlarged view of the pivotal joint of the foldable tent frame as depicted in FIG. 12.

FIG. 14 is an enlarged view of the pivotal support element of the foldable tent frame as depicted in FIG. 12.

(Continued)

FIG. 15 is an enlarged view of an upper roof alignment member and a lower roof alignment member of the foldable tent frame as depicted in FIG. 7, when the upper roof alignment member is received in the lower roof alignment member; and,

FIG. 16 is an enlarged view of the upper and lower roof alignment members of the foldable tent frame as depicted in FIG. 12, when the upper and lower roof alignment members are spaced apart from each other.

The dashed broken lines shown in all figures illustrate portions of the foldable tent frame which form no part of the claimed design.

The dot-dot-dash broken line shown in FIG. 9 represents an alignment line for the roof portion of the foldable tent frame which is included for ease of understanding, and forms no part of the claimed design.

The dot-dash lines shown in FIGS. 10, 11, 13 and 14 represent boundaries of the foldable tent frame claim and themselves form no part of the claimed design.
